OVERALL FASTENER

Filed April 6, 1929

William Wilds,
INVENTOR

BY Victor J. Evans

ATTORNEY

WITNESS:

John J. Evans

UNITED STATES PATENT OFFICE

WILLIAM WILDS, OF BUTTE, MONTANA

OVERALL FASTENER

Application filed April 6, 1929. Serial No. 353,127.

My present invention has reference to a supporting loop for garments, and is primarily designed as a fastening means for the shoulder straps of overalls.

5 The object of the invention is the provision of a supporting loop for this purpose which shall be constructed from a single strand of strong but resilient wire and which includes a button engaging loop and spaced pairs of 10 arms through which the shoulder strap or webbing is threaded, the outer arms having their ends formed with inwardly directed hooks to engage with the edges of the shoulder strap, the construction being such that 15 the greater the pull between the button and the supporting loop the tighter the engagement of the loop with the strap, so that the strap, when adjusted cannot be accidentally moved through the loop.

20 To the attainment of the foregoing, the invention consists in the improvement hereinafter described and definitely claimed.

In the drawings:

Figure 1 is an elevation of the improvement in applied position.

25 Figure 2 is a sectional view approximately on the line 2—2 of Figure 1.

Figure 3 is a perspective view of the improvement per se.

30 As my improvement is especially designed for use in connection with the shoulder straps of overalls, the same has been so illustrated in the drawings. Obviously the improvement may be employed as a supporting loop for other shoulder straps or webbings.

Referring now to the drawings in detail, the numeral 1 designates a folded shoulder strap for overalls and the numeral 2 broadly 40 designates my improvement.

As disclosed by the drawings the improvement is constructed from a single strand of strong but resilient wire. The wire is shaped to form the same with a button engaging loop 45 3, the ends of the loop being rounded outwardly and from thence extended inwardly. These rounded portions are indicated by the numeral 4. The inner ends of the rounded portions are extended outwardly, as at 5, and 50 the said extensions are arranged in parallel-

ism. The portions 5 have their ends rounded in a plane with the loop, as indicated by the numeral 6 and from thence extended to provide the lower or inner parallel arms 7 of the improvement. The inner arms are oppositely directed and have their ends rounded, as at 8, in a plane with the loop 3 and extended to provide oppositely directed outer arms 9. The ends of the arms 9 are bent upon themselves to form the same with inwardly directed hooks 10.

The strap or webbing 1 is threaded between the parts 5 and the lower or inner arms 7 of the supporting loop and likewise between the outer arms 9 so that the hooked ends 10 of the said outer arms are engaged with the edges of the strap 1. An outward pressure between the loop 3 and the strap 1 will result in the inner arms 7 being forced tightly against the fold of the strap and these arms will exert a pull upon the outer arms 9 to force the same toward each other and in tight engagement with the opposite faces of the folded strap and likewise bring the hooks 10 into tight engagement with the edges of the strap so that the strap cannot be accidentally pulled through the loop. As a matter-of-fact the strap can only be adjusted by forcing the hooked ends of the outer arms 9 away from contacting engagement with the edges of the strap.

The simplicity of the construction and the advantages thereof will, it is thought, be perfectly apparent to those skilled in the art to which such invention relates after the foregoing has been carefully read in connection with the accompanying drawings so that further detailed description will not be required.

Having described the invention, I claim:

An adjustable loop to be arranged between the folds of a webbing, comprising a wire member that includes a button-engaging loop whose ends are outwardly directed and rounded upwardly to form the same with parallel arms which are designed to be received in the folded portion of the webbing, said arms having their ends rounded and extended to provide the same with upper 100

parallel arms which are designed to contact with the outer faces of the webbing and the said arms having their ends hooked inwardly to be arranged around the edges of the folded webbing and to contact therewith.

⁵ In testimony whereof I affix my signature.

WILLIAM WILDS.
